C. H. WESTON, OF LOWELL, MASSACHUSETTS.

Letters Patent No. 74,182, dated February 4, 1868.

IMPROVEMENT IN BENCH-HOOKS FOR CARPENTERS' BENCHES.

The Schedule referred to in these Letters Patent and making part of the same.

TO ALL WHOM IT MAY CONCERN:

Be it known that I, C. H. WESTON, of Lowell, in the county of Middlesex, and in the State of Massachusetts, have invented certain new and useful Improvements in Bench-Hooks; and do hereby declare that the following is a full, clear, and exact description thereof, reference being had to the accompanying drawings, and to the letters of reference marked thereon.

In the annexed drawings, making part of this specification, A represents a metallic plate about two inches wide, and from three to four inches in length. This plate is let into a carpenter's work-bench, near one end, until its upper edge is flush with the top of the bench. A suitable recess is formed in the upper side of the plate, as will be set forth, and on the under side are cast two loops or projections, B and C. An open sliding case, G, passes into the loops B and C, and is held in them at and against the bottom of the plate. D represents a metallic bar, which has a rim or flange on its upper end, in which are formed teeth, $\alpha\alpha$. This bar stands in a vertical position, its lower end passing through a hole in the plate A, made to receive it, and also through the case G, which lies beneath the plate. A spring, E, made of coiled wire, connects the lower end of bar D to the loop or projection B, and supports it, keeping it constantly pressed upward. H represents a shaft or bolt, which is provided with a long head, I, and which is cam-shaped on a portion of its surface below this head. This bolt passes through a hole in the plate A, and through the case G, its lower end having a bearing in the loop or projection C. When this bolt is in one position it fits loosely in the case G, but when turned partially around, its cam-surface causes it to fit snugly or very tightly in the case G, forcing it slightly endwise, and securing it firmly in a fixed position. The bolt H is turned by the head or thumb-and-finger piece I. The object of the bar D is to hold lumber or boards in place while being planed, and this bar is set in any required position by turning the bolt H, so that it will cause the case G to draw slightly endwise, and pressing against the bar to hold it securely in position. The spring E throws the bar D up as soon as it is freed, while said bar is held in any desired place by simply turning the bolt H partially around. The object of the recess in the upper side of the plate is to hold the head I, and allow the flange on the upper end of bar D to sink to a level with the top of the table.

The above-described device is designed as an improvement upon my patent of October, 1866, being more economical and simple in the construction.

What I claim as an improvement upon said patent, is—

The bolt H, with its cam-projection, when used with the slotted case G for clamping bar D, the several parts being constructed and operating substantially as specified.

In testimony that I claim the foregoing, I have hereunto set my hand, this 9th day of November, 1867.

C. H. WESTON.
